S. G. Taylor

INVENTOR
Erwin E. A. G. Meyer,

BY
Ernest Thompson
HIS ATTORNEY

UNITED STATES PATENT OFFICE.

ERWIN E. A. G. MEYER, OF DETROIT, MICHIGAN, ASSIGNOR TO MORGAN & WRIGHT, A CORPORATION OF MICHIGAN.

DEVICE FOR TESTING FABRIC.

1,283,856.

Specification of Letters Patent.

Patented Nov. 5, 1918.

Application filed February 24, 1916. Serial No. 30,115.

To all whom it may concern:

Be it known that I, ERWIN E. A. G. MEYER, a citizen of the United States, residing at Detroit, county of Wayne, and State of Michigan, have invented certain new and useful Improvements in Devices for Testing Fabric, of which the following is a full, clear, and exact description.

This invention relates to devices for testing fabric and has for an object to provide a device for determining the breaking point of fabric under conditions approximating conditions existing in the fabric when in use in the product. The device will be described in connection with the testing of fabric for use in the manufacture of tires.

In the carcass or fabric portion of a tire the warp and weft threads are subjected simultaneously to chafing at their intersections. To reproduce as nearly as possible this chafing action while testing fabric the present invention provides means for placing both the warp and weft threads of the fabric under tension simultaneously. The invention provides means for automatically indicating the amount of tension at which the threads break under the above conditions. Thus the breaking points of various grades of fabric may be determined while subjected to approximately the same conditions that exist in a tire in service. A comparison of the results will indicate which grade of fabric is best suited for use in the manufacture of a tire.

The invention can be readily understood from the following description taken in connection with the accompanying drawing, in which:

Figure 1 is a plan view of the device;

Fig. 2 is a side elevation of the device;

Fig. 3 is a detail sectional view of one of the feed nuts;

Fig. 4 is an underneath plan view of the indicating device;

Fig. 5 is a detail view partly in section, showing one of the adjusting members.

Referring now to the drawings in which like characters of reference designate similar parts, 10 designates a standard which is mounted upon a suitable base 11 and is equipped with radially disposed arms 12 extending at right angles to each other. Each arm is provided with a pair of longitudinally extending guides 13. Each pair of guides carries a sliding block 14 having guide lugs

15 on the sides that fit in grooves 16 in the guides. Each block is equipped with a fixed jaw 17 and a movable jaw 18, the latter preferably being set and released by means of a screw 19. The jaws have interfitting faces 20 which obtain a firm grip upon certain of the threads of the fabric to be tested. The jaws of opposite arms 12 are closed upon the same threads in the fabric to be tested, and are then moved simultaneously outward by movement of the blocks 14 longitudinally of the guides 13 through the instrumentality of feed screws 21 and traveling nuts 22 which will presently be described in detail.

Preferably the jaws grasping one set of the threads, for example, the weft threads, are first moved outwardly to place the threads under a predetermined tension which is somewhat less than that required to break the threads. The jaws are automatically locked in this position by pawls 23 which are carried by the blocks 14 and engage in racks 24 on the guides. Then the jaws grasping the other set of the threads, that is, the warp threads, are moved outwardly until the warp threads are stretched to and past the breaking point which is automatically registered as will be presently described. Since the warp threads are stretched over tensioned weft threads approximately the same chafing action will occur at the intersections of both sets of threads as occurs in the fabric of a tire in service. Consequently, the breaks will occur at said intersections as they do in a tire and the amount of tension necessary to cause these breaks will be approximately the same as that required to produce the same result in a tire.

The feed screws 21 for moving the jaws outwardly on the arms are radially disposed and are simultaneously driven from a shaft 25 by means of meshing bevel gears 26 and 27. The shaft 25 is in turn driven by a drive shaft 28 having a worm and gear connection 29 and 30 with the shaft 25. The drive shaft is preferably driven by a motor 31 mounted on the base 11. The motor shaft 32 is connected to the drive shaft by means of a clutch 33 which is thrown into active or released position by a shaft rod 34.

Each traveling nut 22 is formed in halves which are confined against turning by, and carry with them a socket member 35 which is slidably mounted in the guides 13 by guide lugs 36 fitting in the guide grooves 110

16. The socket member is operatively connected to and moves the related slide block 14 as will presently be described. The halves of the nut may be disconnected from 5 the feed screw to facilitate locking the block stationary by its pawl and rack as above described and to permit sliding the nut inwardly over the threads of the feed screw to return the nut to its inward limit of 10 movement. To effect this a cam disk 37 is turnably mounted on the socket member and is formed with eccentric slots 38 which engage pins 39 carried by the halves of the nut. Upon rotation of the disk by means of 15 a handle lever 40 the pins are moved to the outer ends of the slots and draw the halves of the nut out of engagement with the feed screw. Rotation of the disk in the opposite direction moves the halves into engagement 20 with the feed screw.

A right and left threaded adjusting screw 41 connects the socket member on one arm of each pair of opposite arms 12 with the slide block 14 of the arm, and the socket 25 member on the opposite arm is connected to the slide block 35 on the arm by an elliptical spring 42, and member 35' adjustably mounted on the block 35 by means of a right and left threaded screw 35''. The spring 30 also forms the operating member for an indicating device which may be of any desired type but preferably is of a well known type comprising a dial 43 supported by a bracket 44 connected to one side of the 35 spring as shown at 45 and carrying a pointer 46 which may be manually set to indicate any division mark on the dial scale. The dial also carries a second pointer 47 which is connected to the opposite side of the spring 40 by a rack and pinion device 48 and 49 that is operated by distortion of the spring from normal to swing the pointer 47 relatively to the pointer 46.

The operation of the device is as follows: A portion of the fabric to be tested 45 is applied to the jaws, the warp threads being engaged between the jaws of two of the opposite arms and the weft threads being similarly engaged between the jaws of the 50 other two opposite arms. The handle levers 40 of two of the opposite traveling nuts, say for instance, those controlling the slide blocks which operate the jaws grasping the weft threads, are then turned to apply the 55 traveling nuts to the threads of the related feed screws. The machine is then started and when the jaws have moved sufficiently apart to place the weft threads under a predetermined tension, which is indicated by 60 the indicating device, the machine is stopped and the handle levers turned in the opposite direction to release the traveling nuts from the feed screws. The pawls and racks of the jaws operate now to prevent return of 65 the jaws so that the weft threads are main-

tained under the predetermined tension. This tension may be adjusted to the minutest degree by turning the adjusting screw 41—35' to slacken or increase the tension. The handle levers controlling the traveling nuts 70 which operate the jaws grasping the warp threads, are swung to engage the traveling nuts with the related feed screws and the machine is again started and continued in operation until the warp threads are 75 stretched to and past the breaking point which is automatically indicated by the related indicating device. Thus the breaking points of the threads of various grades of fabric may be determined while subjected 80 to approximately the same conditions of tension, chafing, etc., that exist in a tire in service.

While I have described and illustrated the preferred embodiment of my invention, it is 85 to be understood that the various modifications may be restored to within the scope of the appended claims without sacrificing any of the advantages or departing from the spirit of the invention.

What I claim and desire to protect by Letters Patent is:

1. A machine of the class described comprising means for simultaneously exerting a tension on series of crossed threads of a 95 fabric for substantially the entire extent of a given area to be tested, and means for indicating the breaking-point of each series of the tensioned threads independently of the other.

2. A machine of the class described comprising means for simultaneously exerting on series of crossed threads of a fabric a pull longitudinally of the threads and means for indicating the breaking-point of a series 10 of the tensioned threads.

3. A machine of the class described comprising means for simultaneously exerting a tension on series of crossed threads of a fabric while maintaining the shape of the 11 surface of the fabric substantially unaltered and means for indicating the breaking-point of a series of the tensioned threads.

4. A machine of the class described comprising means for simultaneously exerting 11 a tension on series of crossed threads of a fabric, means for indicating the tension of one series of the tensioned threads, and means for indicating the breaking point of a second series of the tensioned threads.

5. A machine of the class described comprising means for gripping intersecting threads of a fabric on opposite sides of their intersections, means for moving the gripping means to tension the threads, and 1 means for indicating the breaking point of a series of the tensioned threads.

6. A machine of the class described comprising means for gripping intersecting threads of a fabric on opposite sides of their 1

intersections, guides for said means arranged at right angles to each other, means for moving the gripping means on the guides to tension the threads, and means for indicating the breaking point of a series of the tensioned threads.

7. A machine of the class described comprising means for gripping intersecting threads of a fabric on opposite sides of their intersections, a shaft concentric with said means, radially disposed feed screws driven by said shaft, traveling nuts on said feed screws operatively connected with and moving said gripping means outward to tension said threads, and means for indicating the breaking point of a series of the tensioned threads.

8. A machine of the class described comprising jaws for gripping intersecting threads of a fabric on opposite sides of their intersections, means for moving the jaws radially apart to tension said threads, a spring receiving the tension of one of the tensioned threads, and means operated by the spring for indicating the breaking point of said thread.

9. A machine of the class described comprising means for exerting a tension on certain threads of a fabric, means for exerting a tension on other threads crossing the first-mentioned threads and means for indicating the breaking-point of said other

threads while maintaining the tension on said first-mentioned threads.

10. A machine of the class described comprising jaws arranged in pairs for gripping intersecting warp and weft threads on opposite sides of their intersections, means for independently moving each pair of jaws outward to separately tension the warp and the weft threads, means for locking one pair of the jaws stationary at a predetermined stage of their outward movement, and means for indicating the breaking point of the threads tensioned by the other pair of jaws.

11. A machine of the class described comprising jaws arranged in pairs for gripping intersecting warp and weft threads on opposite sides of their intersections, means for independently moving each pair of jaws outward to separately tension the warp and the weft threads, means for slackening or increasing the tension of said threads independently of the first named means, means for locking one pair of the jaws stationary at a predetermined stage of their outward movement, and means for indicating the breaking point of the threads tensioned by the other pair of jaws.

Signed at Detroit, Michigan, this 18th day of February, 1916.

ERWIN E. A. G. MEYER.
